UNITED STATES PATENT OFFICE.

JOSEPH W. TAGGART, OF WATERTOWN, NEW YORK, ASSIGNOR TO TAGGART BROTHERS COMPANY, INC., OF WATERTOWN, NEW YORK, A CORPORATION OF NEW YORK.

PAPER BAG.

Application filed March 5, 1925. Serial No. 13,244.

This invention relates to paper bags in general, and has especial reference to the production of relatively large heavy and coarse bags that are commonly made from manila rope and other stock from which strong paper bags are made, and are usually employed for packing coal, cement, plaster, flour and various other pulverized products.

The object of the present invention is to improve the construction of paper bags of the class named, and particularly the method of forming and closing the bottom ends of the bag, which are usually made from prepared tubular stock, whereby a more effectual seal of the various bottom joints may be effected, and whereby the bottoms may be strongly reinforced and rendered less liable to develop defects and faults, such for example as, bursting or gaping at the pasted joints, thereby allowing the contents of the bags to escape. A further object is to slit certain portions of the bottom end of the tubular blanks, and then to crease the opposite side portions adjacent the slits, in a manner to effect the substantial overlapping of the several series of bottom flaps, where formerly but one series of flaps have been overlapped. A further object is to apply the adhesive, by which the lap-joints are cemented and sealed, to the outer face of the bottom after one series of flaps have been folded towards each other, and while the other series of flaps are still extended, the zone of said adhesive being elongated, and the linear dimension of said zone being disposed in the line of the longitudinal axis of the tube, whereby the said adhesive may be applied at one operation, to the corresponding portions of both series of flaps, for effecting a powerful seal of the primary, as well as the secondary joints of the bottom, when all of said flaps are finally folded. And a particular object is to provide a bag of the class suitable for packing and transporting carbon-black, and similar extremely light and fluffy materials, whose particles are as light and as searching as air, and are therefore liable to escape through the smallest gaps or openings in the joints, during the handling of the filled bags.

I attain these objects by the means set forth in the detailed description which fol-

lows, and as illustrated by the accompanying drawing, in which—

Figure 1 is a plan view of a prepared tubular blank, from which my improved bag is made; showing by dotted lines the creases by which the several bottom end flaps are formed. Fig. 2 is an edge view of the tube; showing the bottom end partially folded. Fig. 3 is a front face view of the tube shown in Fig. 2; showing the opposite lateral flaps folded inwardly and substantially overlapped in the line of the longitudinal center of the tube; the oppositely arranged side flaps being extended; also showing the elongated shaded zone which represents the adhesive. Fig. 4 is a similar view, showing the side flaps folded towards each other, for covering the lap-joint of the lateral flaps; also showing the overlapping of the side flaps which adhere to each other as well as to the lateral flaps. Fig. 5 is an edge view of the bag shown in Fig. 4. Fig. 6 is a view of the bottom end, taken in the direction of the arrow in Fig. 3; showing the overlapping of the lateral flaps. Fig. 7 is a broken plan view of a modified construction, showing the lugs of the side flaps folded inwardly upon the joint of the lateral flaps prior to the applying of the paste, by which the side flaps are secured. And Fig. 8 is a broken edge view of the modified construction illustrated in Figure 7.

In the drawing, 2 represents the tubular blank from which the bag is formed, and comprises front and rear sides 2^a—2^b, which are joined by lateral folds 2^b, the side 2^b being formed by overlapping similar lateral portions 2^a—2^b, the joint or seam, as 2^a, of the tube being disposed substantially in the line of the longitudinal axis of the tube, and being suitably pasted, in a well-known manner. 3 represents the top, and 4 the bottom end of the blank. Preparatory to forming the usual bottom flaps, the end 4 is slitted longitudinally for providing similar integral front and rear lugs or tongues 2^a—2^b, and the said end portion is also creased, as shown in Fig. 1, for facilitating the subsequent angular folding and overlapping of the portions of the tube that comprise the bottom of the completed bag, as may be understood by viewing Figs. 1,

2, 3 and 6. After the tube 2 is slit and creased as described, it is fed into the usual bottoming machine (not shown), which initially spreads in a well-known manner 5 the open bottom, and then folds the front and rear lateral triangular portions 5—5' on the angular creases 5^a, for producing the diamond-shaped configuration, shown in Fig. 3. This brings the corresponding bottom end margins 4'—4^a parallel to each other, and also overlaps the said margins, as at 4^b, the said lap preferably being located substantially in the line of the longitudinal seam 2^x, as shown in Figs. 3, 6 and 15 7. This leaves the lugs 2^e—2^f extended beyond and in line with the joints 2^x and 4^b. While the bottom end is still extended, as shown in Figs. 2 and 3, the tube is carried along by the machine, to a point where an 20 adhesive, (see shaded portions of Figs. 3 and 7), is applied preferably in the form of an elongated zone or strip, as 7, which coincides with and preferably extends laterally beyond the joint 4^b, the said adhesive preferably being applied to the marginal portions of the lateral flaps 5—5', as well as to the lugs 2^e—2^f, at one operation, as shown. After the adhesive 7 is applied, the tube 2 is again carried forward in the machine, 25 and the front side flap 8, which comprises corresponding portions of the flaps 5—5', and is rendered foldable by the transverse and longitudinal arms of the crease 8' of the front side 2' of the tube, is next folded inwardly upon, and partially overlaps, the lateral flaps 5—5', after which the rear or opposite side flap 9, which comprises similar portions of the flaps 5—5' and is foldable on the creases 9', is finally folded inwardly upon the remaining portions of the lateral flaps, and also upon the side flap 8, as best seen in Fig. 4. This completes the folding and sealing of the bottom of the bag. It will be understood from the foregoing that the lateral flaps 5—5', as well as the side flaps 8—9, are all treated with the adhesive 7, as shown in Figs. 3 and 7, and when the side flaps 8 and 9 are folded, as 30 shown in Fig. 4, the complete adhesion of all of the bottom parts is effected by the meeting of the pasted portions of the several flaps, and in a manner to effectually seal the portion of the joint 4^b, which lies between the creases 8' and 9' (see Fig. 3), as well as the portions of the said joint, which extends across the adjacent portions of the side flaps. The lug 2^e also contributes its share to the sealing of the joint 4^b, and both of the lugs (2^e—2^f) also perform a particular and valuable function in that they effect the sealing of openings 10, which occur at the bases of said lugs, (see Figs. 3 and 6), which might, except for the provision of said lugs, gape open. The joint 4^b being disposed well within the zone of

the adhesive, more or less of the paste 7 enters between the overlapped margins 4'—4^a, and tends to seal said joint independently of the sealing effected by the side flaps 8 and 9. This pasting and sealing of the joints 4^b is enhanced somewhat by the serrating of the edge 4', which greatly increases the marginal contour that receives the adhesive. In practise, this serrated edge, by reason of the capillary action of the paste, is found to be effectively sealed before the side flaps are folded. 70

In Figs. 7 and 8, the lugs 2^e—2^f are shown folded inwardly upon the side flaps, for closing the open ends 10, before the final 80 pasting and folding of the side flaps, 8 and 9. This modification, while necessitating one or more extra operations, has the merit of more effectively sealing the overlapped ends 10 of the lateral flaps. 85

My invention is extremely simple, and can be applied to paper bags without any extra labor and cost, as compared with the old styles or makes of bags, and the said improvement may be applied to tubular blanks 90 that have been previously made and stored away long enough for the main side joints 2^x to become dried and set, instead of performing the bottom-closing operations immediately after the tubes have been formed, 95 as has been the custom heretofore.

Obviously some changes or modifications of the method and the resulting structure of the bags may be made, without departing from the spirit of the invention, but I wish it to be understood that the essential and valuable features of my invention, to which I lay particular claim in this application, reside in the slitting of the end margin 4'—4^a of the tube 2, for providing the tongues 2^e—2^f, and the provision of the angular creases 5^a, which diverge from the bases of the said tongues, and by means of which the lateral portions 5—5' may be folded in a manner to overlap the margins 4'—4^a, for effectually closing and sealing the normal bottom embracing the diamond-shaped field, shown in Figs. 3 and 7, in combination with the construction and arrangement of the integral side flaps 8 and 9, which are adapted 105 to be folded and overlapped upon the joint 4^b, in a manner to effect a double seal, and at the same time suitably reinforcing the bottom of the bag, at its weakest points. 110

Having thus described my invention, what I claim, is— 120

A paper bag comprising a tubular blank having its front and back wall portions at its bottom end each provided centrally of its side edges with a pair of relatively short closely arranged longitudinal slits forming similar relatively narrow short tongues, the blank being formed with creases diverging from the bottom of said slits whereby the lateral portions between said creases and the 125 130

bottom end margins may be expanded and folded towards each other and providing for effecting the overlapping of the bottom marginal edge portions in the line of the longitudinal axis of the blank for substantially the full breadth of the expanded bottom, and an adhesive applied to a zone embracing the overlapped marginal portions and said tongues, said folded lateral por-

tions at either side being folded transversely 10 substantially midway of their length in overlapping relation upon the overlapped marginal edge portions and cemented thereto and to each other, said tongues being first folded inwardly upon and cemented to the 15 said folded lateral portions.

In testimony whereof I affix my signature.
JOSEPH W. TAGGART.
